UNITED STATES PATENT OFFICE.

JOHN CSISKO, OF WEST NEWTON, PENNSYLVANIA.

METALLIC TIE AND RAIL-FASTENER.

1,005,000.

Specification of Letters Patent.

Patented Oct. 3, 1911.

Application filed May 5, 1911. Serial No. 625,147.

To all whom it may concern:

Be it known that I, JOHN CSISKO, a subject of the King of Hungary, residing at West Newton, in the county of Westmoreland and State of Pennsylvania, have invented certain new and useful Improvements in Metallic Ties and Rail-Fasteners, of which the following is a specification, reference being had therein to the accompanying drawing.

This invention relates to a metallic tie and rail fastener and the objects of my invention are to substitute metal for wood in the ties or sleepers of a railroad track, and to furnish the metallic ties with fasteners that can be easily and quickly placed in position to positively retain rails upon the tie and prevent lateral and vertical displacement of the rails.

Further objects of my invention are to provide rail fasteners that can be used in connection with single rails or double rails adjacent to a switch, and to accomplish the above results by a mechanical construction that is simple, durable and easy to install.

These and such other objects as may hereinafter appear are attained by a mechanical construction that will be hereinafter specifically determined and then claimed.

Reference will now be had to the drawing, wherein:

Figure 1 is a plan of a portion of the tie provided with a rail fastener in accordance with this invention. Fig. 2 is a longitudinal sectional view of the same. Fig. 3 is a perspective view of a detached fastener. Fig. 4 is a plan of the tie showing a fastener designed for two rails. Fig. 5 is a longitudinal sectional view of the same, and Fig. 6 is a perspective view of a detached double fastener.

A metallic tie in accordance with this invention comprises a solid oblong body 1 having its upper face adjacent to each end 45 thereof cut away to provide a transversely-extending relatively wide groove with the bottom 2 thereof constituting a rail seat. As shown in Fig. 2 one side wall 3 of the groove overhangs the bottom of the groove 50 thereby providing what is termed an outer rail fastener adapted to extend over the outer side of the base flange 4 of the rail 5, the latter being mounted upon the bottom 2 of the groove at one side thereof and has its 55 outer longitudinal edge abutting against the inner portion of the overhanging wall 3.

The other side wall of the groove is indicated at 9 and is vertically disposed. The bottom 2 of the groove at a point between the base flange 4 and the wall 9 is formed with a transversely-extending dove-tail channel 6 for the purpose to be presently referred to.

Mounted within the transversely-extending groove and as shown in Fig. 2 is an inner rail fastener consisting of a body portion 8 rectangular in plan and which has depending from and disposed centrally of its lower face a dove-tail tongue 7 adapted to be positioned in the channel 6 whereby the inner fastener 8 is connected to the body 1. That portion of the lower face of the body portion 8 between one side of the tongue 7 and the end 9^a extends in a plane parallel with the upper face of the body portion 8 as indicated at 9^b. That portion of the lower face of the body portion 8 between the other side of the tongue 7 and the end 10 is provided with a shoulder as at 10^a and that part of the lower face of the body portion 8 between the shoulder 10^a and the tongue 7 extends in a plane parallel with the upper face of the body portion 8, while that part of the lower face of the body portion 8 between the inner terminus of the shoulder 10^a and the end 10 is beveled upwardly as at 10^b. When the inner fastener is mounted in position the shoulder 10^a abuts against the inner longitudinal edge of the base 4 of the rail and the beveled portion 10^b overlaps the upper face of the inner side of the base 4 of the rail while the end 9^a abuts against the vertical wall 9.

The body portion 8 is formed with a vertically-disposed opening 11 having the wall thereof screw-threaded and said opening 11 registers with the socket 12 formed in the body 1. The upper end of the opening 11 is enlarged as at 13 for the reception of the head 14 of a screw bolt 15 which extends through the openings 11 and into the screw-threaded socket 12 and engages with the threaded walls of said opening and socket thereby retaining the inner fastener upon its seat.

In Figs. 4 to 6 inclusive the tie body is provided with a transversely-extending groove for the reception of a pair of rails 17 retained in position through the medium of what is termed a duplex fastener. The bottom wall of the groove is indicated by the reference character 16 and each side wall

by the reference character 18. The side walls 18 overhang the bottom 16 of the groove, said bottom constituting a seat for the rails. When the rails are mounted in 5 the transversely-extending groove they abut against the inner portions of the side walls 18 and the side walls 18 also overlap the bases of the rails 17 as clearly shown in Fig. 5. The bottom 16 of the transversely-extending groove is formed centrally with a dove-tail channel 20 for the purpose to be 10 presently referred to.

The duplex fastener consists of a body portion 19 rectangular in plan and having 15 its lower face provided centrally with a transversely-extending dove-tail tongue 21 adapted to be seated in the dove-tail channel 20 whereby the body portion 19 is coupled to the body and as clearly shown in Fig. 5. 20 The lower face of the body portion 19 between the tongue 21 and each end 22 of said body portion 19 is provided with a transversely-extending shoulder 23 and that part of the lower face of the body 19 between the 25 outer terminus of the shoulder 23 and the tongue 21 extends in a plane parallel with the upper face of the body portion 19, as at 25, while that part of the lower face of said body portion 19 between the inner terminus 30 and the shoulder and the end of the body portion is upwardly beveled as at 24. When the duplex fastener is fastened in position the shoulders 23 abut the longitudinal edges 35 of the rails 17, the beveled portions 24 overlap the bases of the rails and the portions 25 seat upon the bottom wall 16 of the groove. The duplex fastener is secured to the body by a hold fast device and in the same manner as that referred to in Fig. 2, like reference characters being used.

What I claim is:

1. In combination, a metallic tie having one end thereof provided with a seat for a rail and further provided with means overhanging the base of the rail and constituting 45 an outer rail fastener, an inner rail fastener provided with a depending tongue engaging in said body for connecting said inner rail fastener thereto, said inner rail fastener 50 having its lower face between one side of the tongue and one end thereof formed with a

transversely-extending shoulder, said lower face of said inner rail fastener between the shoulder and the tongue extending in a plane parallel with the upper face of said 55 inner fastener, said inner fastener having its lower face between the shoulder and one end upwardly beveled, said shoulder adapted to abut against the base of the rail and said beveled portion overhanging the base of the 60 rail, and means extending through said inner fastener centrally thereof and engaging in said body for securing the inner fastener thereto.

2. In combination, a tie body provided at 65 one end with a seat for a pair of rails and further provided with means overhanging the bases of the rails and constituting outer rail fasteners, an inner rail fastener provided with a depending tongue engaging in 70 said body for connecting said inner rail fastener thereto, said inner rail fastener having its lower face between one side of the tongue and one end thereof formed with a transversely-extending shoulder, said lower 75 face of said inner rail fastener between the shoulder and the tongue extending in a plane parallel with the upper face of said inner fastener, said fastener having its lower face between each side of the tongue and an 80 end provided with a transversely-extending shoulder, the parts of the lower face of the fastener between the sides of the tongue and the shoulder extending parallel with the upper face of the fastener and the parts of 85 the fastener between the shoulder and the ends thereof being upwardly beveled, the beveled portions being oppositely disposed with respect to each other, said shoulder adapted to abut against the edges of the 90 bases of a pair of rails and said beveled portions overlapping the bases, and means extending through said inner fastener centrally thereof and engaging in said body for 95 securing the inner fastener thereto.

In testimony whereof I affix my signature in the presence of two witnesses.

JOHN CSISKO.
